(57) **CLAIM**

The ornamental design for the “chair,” as shown and described.

DESCRIPTION

FIG. 1 is a front perspective view of the chair.

FIG. 2 is a back perspective view of the chair.

FIG. 3 is a right side view of the chair.

FIG. 4 is a front view of the chair.

FIG. 5 is a left side view of the chair.

FIG. 6 is a back view of the chair.

FIG. 7 is a top view of the chair; and,

FIG. 8 is a bottom view of the chair.

The short dashed lines shown on the backrest and seat cushions are understood to represent stitching.

1 Claim, 8 Drawing Sheets
